UNITED STATES PATENT OFFICE.

JAMES E. F. LELAND, OF NEW YORK, N. Y., ASSIGNOR TO H. A. LELAND,
OF SAME PLACE.

IMPROVEMENT IN WOOD-TURNING LATHES.

Specification forming part of Letters Patent No. 58,947, dated October 16, 1866.

To all whom it may concern:

Be it known that I, J. E. F. LELAND, of the city, county, and State of New York, have invented new and useful Improvements in Machines for Turning Irregular Forms; and I do hereby declare that the following is a full, clear, and exact description thereof, which will enable others skilled in the art to make and use the same, reference being had to the accompanying drawings, forming part of this specification.

The present invention relates to a machine for the turning of irregular forms, and consists in suspending the material which is to be turned upon centers of a carriage, arranged to slide in a suitable way or groove of the bed-piece of the machine, in combination with one or more cutters, so arranged in connection with the said carriage and operated that as the material is carried along to the said cutters, they will be made to so act upon the material as to produce the form desired thereon, in a manner as will be hereinafter particularly explained, reference being had to the accompanying plate of drawings, in which—

Figure 1 is an elevation of the front end of the machine; Fig. 2, a central longitudinal vertical section taken in the plane of the line x x , Fig. 1; Fig. 3, a partial horizontal section taken in the plane of the line y y , Fig. 1.

Similar letters of reference indicate like parts.

A in the drawings represents the bed-piece of the machine; B, a carriage or slide, arranged to move in a groove or way, U, of the said bed-piece A, and in the direction of its length. This carriage B has at each end a fixed standard or puppet, D, between which the material to be turned is placed, and there suspended or fixed upon suitable centers at each end. E, a rack or toothed bar formed along one edge of the carriage B, and extending in the direction of and for a portion of its length, with the teeth of which rack a toothed or gear wheel, F, engages, that is suspended and turns upon a center of the upright back plate, G, of the bed-piece A.

On the front face of the gear-wheel F a flat disk or wheel, H, is secured, so as to revolve in conjunction therewith, that, upon its edge or periphery, is made of a cam or eccentric

shape. Against this cam-edge of the wheel H one end of a hollow sleeve or tube, I, abuts, which tube is arranged to move and slide in a concentric tube, J, fixed or secured upon suitable supports K therefor. The tube I extends in the direction of the length of the sliding carriage B, and by the tube J, which holds it, it is arranged so as to be concentric with the centers carrying the material to be operated upon or turned, and in an intermediate position between the supporting-puppets of the carriage, the said material consequently passing through the center of the tube I, as is obvious without any further explanation.

The opposite end of the tube I to that which bears against the cam-edge of the wheel H is made of a conical shape, or, in other words, with beveling or inclined sides, terminating in a square shoulder, a, that fits against a square shoulder, b, formed upon the inside of the surrounding tube J for the tube I.

The surrounding tube J, at the conical-shaped end of the interior tube, I, terminates in a flat head-plate, K, in radial grooves or ways L of which plates or blocks M, carrying or holding cutters N, are arranged so as to move in and out, these plates or blocks at their inner ends bearing against the conical-shaped end of the tube I, where, by means of an encircling elastic band or strap applied to the outside edge of the head-plate K and embracing the outer ends of the said blocks M, they are firmly held and retained.

From the above description of the construction and arrangement of the various parts composing my improved machine for turning irregular forms, it is plain to be understood that if the gear-wheel F be revolved in the proper direction the slide carrying the material to be turned or acted upon will be moved forward, while at the same time, through the action of the eccentric or cam-shaped edge of the disk H, attached to such gear-wheel upon one end of the tube, together with the action of the elastic band or strap upon the cutter-holder plates, the cutters are made to act upon and held against the material, cutting the same and turning it to a form which, in the direction of the length of the material, must be irregular, either more or less, according to the peculiar or irregular shape of the cam-edge

hereinbefore referred to, but in a transverse direction, at any point of its length, always having the form of a perfect circle and concentric with the center or axis of the material.

By removing the eccentric or cam-shaped disk from the cam-wheel F and substituting another for it having a different shape or form of its cam-edge, any desired irregularity of form in the direction of the length of the material can be produced, as is obvious without any further explanation.

I claim as new and desire to secure by Letters Patent—

The slide B, carrying the material to be turned, cam or eccentric wheel H, sliding tube I, concentric tube J, having cutters N, when all arranged together substantially in the manner and for the purpose described.

The above specification of my invention signed by me.

JAMES E. F. LELAND.
